UNITED STATES PATENT OFFICE.

GEORGE W. STAPLES, OF MOUNT CRAWFORD, VIRGINIA.

DISH-WASHER.

1,332,080.

Specification of Letters Patent. Patented Feb. 24, 1920.

Application filed May 31, 1918. Serial No. 237,527.

To all whom it may concern:

Be it known that I, GEORGE W. STAPLES, a citizen of the United States of America, residing at Mount Crawford, in the county of 5 Rockingham and State of Virginia, have invented new and useful Improvements in Dish-Washers, of which the following is a specification.

The invention relates to devices for washing or cleansing dishes and the interior of 10 bottles, drinking glasses and the like.

Its principal object is to provide a device of this kind which may be attached on the top of a table, so that a dish pan may be 15 placed under it to permit the vital parts of the machine to be operated above the dish pan.

A further object of the invention is to provide detachable mop and brush members 20 with an efficient means for rotating them whereby the cleansing operation on dishes may be economically performed.

A still further object is to provide a device of this kind which is simple in construction, 25 durable and effective in operation and which may be manufactured at low cost.

Other and further objects will appear in the following description.

To the exact embodiment in which the invention is shown, it is not to be restricted. 30 Actual practical application may make manifest certain desirable changes or alterations and the right is claimed to make any which no not deviate from the scope of the subjoined claim.

In the accompanying drawings:

Figure 1 is a side elevation of the invention in operative position over a dish pan which is shown in section.

Fig. 2 is an end elevation.

Fig. 3 is a detail perspective view of one of the feet of the frame.

Fig. 4 is a detail perspective view of the other of the feet of the frame.

Referring to the drawings, there is indicated at 1 the top surface of a table on which the device is attached. The device comprises essentially a frame 2, whose legs 5 and 6 terminate in the feet 3 and 4 respectively which provide means for attaching the frame to the table. The foot 3 is slotted in the direction of the length of the frame providing a recess 7 while the foot 4 is slotted in the direction of the width of the 55 frame, thus leaving the recess 8.

The recess 7 of the foot 3 engages a suit-

able stud or screw 9 which is set in the table, while the recess 8 engages a thumb screw 10 which threads into the table but is designed to be removable, so that the frame may be 60 attached to or detached from the table.

At a point below the top of the frame 2, a longitudinal member 11 is attached between the inner faces of the legs 5 and 6 and this member is designed to receive and support 65 the spindles 12 both of which have their upper ends journaled in the member 11, through which these upper ends pass to receive the bevel gears 13.

A shaft 14 is journaled in both the legs 5 70 and 6 and between the member 11 and the upper end of the frame 2, the shaft being prevented from longitudinal movement by a detachable collar 15 which abuts the outer 75 face of the leg 5 and by a crank 16 whose hub abuts the outer face of the leg 6. The shaft 14 carries bevel gears 17 so positioned on it as to mesh with the gears 13 and to drive the latter when the shaft 14 is turned.

The spindles 12 are bored longitudinally 80 on the ends remote from the gears 13 and these bored portions of the spindles provide sockets for receiving the stems of the brush member 18 and mop member 19, these stems and their attendant brush and mop being 85 held in place in the sockets by thumb screws 20 which thread radially through the spindles 12 and bear upon the stems. The loosening of either thumb screw 20 will permit the removal of either the brush or the mop 90 so that two mop members may be used by replacing the brush member with a mop or two brush members by replacing the mop member by a brush or any other suitable combination which is desired. 95

In the use of the device, the frame 2 is attached to the table 1 as aforesaid, when a suitable dish pan containing the dishes to be washed is placed below the washing members 18 and 19, the legs 5 and 6 of the frame being a sufficient distance apart to permit the placing of the wash pan between them. The crank 16 is then turned, thus imparting rotary motion to the brush 18 and mop 19 both of which run at relatively high speed, 100 because of a relatively high gear ratio existing between the gears 17 and 13. The dishes being cleansed are brought individually against the brush member 18 which serves to clean off all dirt. The same dish may then 105 be wiped dry by the mop member 19 if the latter has not been used for cleansing and 110

has, therefore, not been made wet. The brush 18 will effectively reach the inside of bottles and glasses and the like and the mop 19 will also reach the interior of these articles to perform the wiping operation.

If it is not desired to use the mop 19 for drying it may also be used for cleansing flat dishes while the brush is used for cleansing bottles and the like.

10 Further the device may be used first for cleansing the dishes and thereafter used for drying the same, the cleansing mop and brush being removed after the cleansing operation by the loosening of the thumb screws 20 and replaced by suitable reserve mops similar to the mop 19 which reserve mops may be used for performing the drying operation.

20 The invention having been described, what is claimed as new and useful is:

In a device of the kind set forth, the combination of a frame consisting of a pair of spaced legs, a longitudinal member mounted in the frame and connected to the two legs,

the member being disposed below the plane 25 of the top of the frame, a pair of spindles spaced from each other and from the legs of the frame, the said spindles being vertically disposed and having their upper ends journaled in said member, a longitudinal shaft 30 rotatably mounted in the frame and disposed between said member and the top of the frame, geared connections between said shaft and said spindles, means for rotating said shaft to impart rotary motion to the 35 spindles, removable cleansing and wiping members carried respectively by the two spindles, and means for removably attaching the frame to the top of a table or the like, whereby the said cleansing and wiping members may be disposed within a dish pan and the latter moved within a specified radius to permit the operation of said members upon the contents of the pan as herein shown and specified.

45 In testimony whereof I affix my signature.

GEO. W. STAPLES.
